G. L. WACKEROW

WRENCH

Filed Jan. 9, 1926

INVENTOR.
G. L. WACKEROW.
BY HIS ATTORNEYS.

Williamson Reiff & Williamson

UNITED STATES PATENT OFFICE.

GEORGE L. WACKEROW, OF MELLETTE, SOUTH DAKOTA.

WRENCH.

Application filed January 9, 1926. Serial No. 80,307.

This invention relates to a wrench and particularly to an adjustable wrench.

It is an object of this invention to provide a simple and efficient type of adjustable wrench comprising a fixed jaw and a movable jaw, means being provided for moving the movable jaw by a swinging movement of the handle in the same direction as the handle is swung for turning the nut operated upon, said wrench being so constructed that said means may be disengaged from the movable jaw and the handle swung for another turning movement on the nut.

It is also an object of this invention to provide a wrench comprising a head having a fixed jaw and a movable jaw guided therein, said movable jaw having a rack formed thereon which is engaged by a gear rigidly carried at one end of a handle pivoted to

said head.

It is a further object of the invention to provide a wrench, as set forth in the preceding paragraph, having means for holding said gear in engagement with said rack, but in which said gear is movable axially out of engagement with said rack, whereby said handle may be swung without moving said movable jaw.

These and other objects and advantages of the invention will be fully set forth in the following description made in connection with the accompanying drawings in which like reference characters refer to the same parts throughout the several views, and in which,

Fig. 1 is a plan view of the wrench, different positions of the handle and movable jaw being indicated in dotted lines;

Fig. 2 is an edge view of the wrench, as seen from the bottom of Fig. 1, in which a different position of the gear and handle is indicated in dotted lines;

Fig. 3 is a vertical section on the line 3—3 of Fig. 2, as indicated by the arrows; and

Fig. 4 is a vertical section taken on the line 4—4 of Fig. 1, as indicated by the arrows.

Referring to the drawings, a wrench is shown comprising a head 4 having formed thereon a fixed jaw 4^a and having extending at one side a flange 4^b. The head 4 also has a portion 4^c extending over the flange 4^b but spaced therefrom, said portion forming with the flange 4^b and the head 4^a, a channel

at the wide portion of the fixed jaw 4^a, the portion 4^c extending beyond the fixed jaw 4^a being thus in the form of a projecting arm. A movable jaw 5 is provided shaped similarly to the fixed jaw 4^a and reversely disposed in relation thereto, which movable jaw 5 has a projecting arm 5^a having rack teeth 5^b formed on one side thereof. The arm 5^a is adapted to move and be guided between the flange 4^b and the portion 4^c. A handle member 6 is provided of convenient length and of a form adapted to be comfortably grasped in the hand, which handle has an aperture 6^a at its outer and larger end. Said handle tapers inwardly and has formed thereon and thus rigidly secured thereto a gear or partial gear 6^b. The handle and gear are pivoted to the flange 4^b about the axis of said gear. While various forms of pivots might be used, in the embodiment of the invention illustrated, the gear 6^b is pivoted on a stud 7 having a reduced portion extending through the flange 4^b and riveted at one side thereof. The stud 7 extends some distance above the gear 6^b with the same diameter as the bore of said gear and a plate 8 has one end secured to the top of stud 7 by a grooved headed screw 9 threaded into the top of stud 7, said spring extending a short distance at each side of stud 7. The spring 8 extends some distance over the handle 6 and is secured at its other end to said handle by the rivet 10. A pin 11 is secured in the outer end of the arm 4^c and flange 4^b and constitutes a stop for the movable jaw 5.

In operation, the wrench will be held in the hand with the hand grasping handle 6, which handle will be approximately in the dotted line position shown at the top of Fig. 1. At this time, the movable jaw will be in its outer position, as shown in Fig. 1. The jaws are now placed in position to embrace the nut and the handle is swung in a clockwise direction or toward the full line position in Fig. 1. This movement rotates the gear 6^b and moves the rack 5^b and the movable jaw 5 toward the fixed jaw 4^a. As soon as the movable jaw 5 engages the nut its movement is stopped, and further movement of handle 6 will then turn the nut, the jaws being urged and maintained in tight engagement with the nut by the gear 6^b. The handle 6 is now swung to turn the nut as far as it is convenient to swing the handle. The

operator then rests his thumb on the top of screw 9 and presses upwardly with his fingers on the bottom of handle 6 adjacent gear 6^b. The handle and gear are thus 5 lifted upwardly to the dotted line position shown in Fig. 2, gear 6^b thus being raised above and out of engagement with rack 5^b. The handle can now be swung in a counter-clockwise direction to substantially the position shown in dotted lines at the top of 10 Fig. 1. The gear 6^b and handle are then released by the fingers and the gear immediately assumes its position on flange 4^b in engagement with rack 5^b; the gear and handle being urged into this position by spring 8. The operator will now again swing the 15 handle 6 through another angle to further tighten the nut. This operation can be quickly repeated until the nut or bolt is 20 tightened as much as desired. If it is desired to turn the nut in a reverse direction the wrench is quickly lifted from the nut and turned into position with the gear on the underside and the jaws applied to the 25 nut. The nut can then be turned in a reverse direction or in a counter-clockwise direction to be loosened in the same manner as already described for turning the nut in a 30 clockwise direction. It will be readily seen that the inner end of spring 8 forms a stop for the gear 6^b when the same is movable axially out of engagement with rack 5^b. The parts are preferably assembled before the 35 pin 11 is placed in position. After the pin is in position it will be seen that the movable jaw cannot be entirely detached or moved out of engagement with gear 6^b, pin 11 also holding and bracing arm 4^c.

From the above description it is seen that 40 applicant has provided a very simple and efficient adjustable wrench. The wrench can be used on a wide range of sizes of nuts and the wrench can be very quickly operated. It is unnecessary to remove the 45 wrench from the nut and re-engage the nut for each annular turning movement. The nut can thus be rapidly tightened or loosened. The wrench quickly engages the nuts of different sizes and the nut is very 50 firmly engaged, especially by the outer end of the movable jaw. The objectionable creeping or lost motion effect present in many adjustable wrenches is thus eliminated and the nut is always closely and tightly 55 engaged. The device comprises very few parts and can be easily and inexpensively and ruggedly made. The device has been amply demonstrated in actual practice and found to be very successful and efficient.

60 It will, of course, be understood, that various changes may be made in the form, details, arrangement and proportions of the parts without departing from the scope of applicant's invention, which, generally stated, consists in a device capable of carry-

ing out the objects above set forth, such as shown and described and defined in the appended claims.

What is claimed is:

1. A wrench having in combination, a 70 head having a fixed jaw thereon, said head having a flange projecting at one end thereof, a movable jaw guided in said head for movement toward and from said fixed jaw and having a rack formed on one side thereof, a handle pivoted to said flange and carrying a gear rigid therewith meshing with said rack, said gear being movable axially out of engagement with said rack whereby 75 a new purchase may be obtained by re-engagement of said rack and gear.

2. A wrench having in combination, a head having a fixed jaw thereon, a movable jaw guided for movement toward and from said fixed jaw and having a rack formed 85 thereon, a handle pivoted to said head and carrying a gear rigid therewith, a pivot for said handle co-axial with said gear on which said gear and handle is slid able whereby said gear may be moved axially out of engagement with said rack, and means holding said gear normally in engagement with said rack.

3. The structure set forth in claim 2, said last mentioned means comprising a spring 95 engaging said handle and extending over said pivot and constituting a stop for said gear in its axial movement.

4. A wrench having in combination, a head having a fixed jaw thereon, a movable jaw guided for movement toward and from 100 said fixed jaw, a handle pivoted to said head and having means rigid therewith normally engaging said movable jaw to move the same toward and from said fixed jaw by swinging movement of said handle, said means being movable out of engagement 105 with said movable jaw in a direction substantially at right angles to the side of said jaw to permit swinging movement of said handle without moving said movable jaw 110 and means normally holding said handle in engagement with said movable jaw.

5. A wrench having in combination, a head having a fixed jaw thereon, a movable jaw guided for movement toward and from 115 said fixed jaw and having spaced means formed thereon, a handle pivoted to said head and having means rigid therewith normally engaging said spaced means to move said movable jaw toward and from said 120 fixed jaw, said means being movable out of engagement with said movable jaw in a direction parallel with the axis about which said handle swings to permit swinging movement of said handle without moving said 125 movable jaw.

6. A wrench having in combination, a head having a fixed jaw thereon, said head having a flange projecting at one end thereof, a movable jaw guided in said head for 130

movement toward and from said fixed jaw having a rack formed thereon, a handle pivoted to said flange and carrying a gear rigid therewith meshing with said rack, a stud 5 fixed in said flange to which said handle is pivoted, disposed co-axially with said gear, a plate spring secured to said stud and extending over the edge of said stud, the other end of said spring engaging said handle, said spring holding said gear in mesh with said rack but being flexible away from said handle and gear, said gear being moved 10 out of mesh with said rack in a direction parallel with the axis of said stud when said 15 spring is so flexed.

7. A wrench having in combination, a head having a fixed jaw at one side thereof and having a flange projecting at its opposite side, said flange having a flat surface, 20 a movable jaw guided in said head for movement toward and from said fixed jaw and

having a rack formed thereon, a handle pivoted to said flange and carrying a gear rigid therewith meshing with said rack and resting on said flat surface, a stud fixed in said flange extending through said gear and above the same a distance greater than the thickness of said gear, said gear and handle swinging about said stud as a center, an elongated plate spring having one end 25 secured to the top of said stud, extending longitudinally of said handle and having its other end bent downwardly and secured to said handle whereby said spring normally holds said gear in engagement with said 30 rack but said gear and handle can be moved against the tension of said spring parallel to the axis of said stud to move said gear out of engagement with said rack.

In testimony whereof I affix my signature.

GEORGE L. WACKEROW.
